UNITED STATES PATENT OFFICE.

SAMUEL M. LANGSTON, OF CAMDEN, NEW JERSEY.

TUBE-MAKING MACHINE.

981,774.

Specification of Letters Patent. Patented Jan. 17, 1911.

Application filed August 30, 1910. Serial No. 579,628.

To all whom it may concern:

Be it known that I, SAMUEL M. LANGSTON, a citizen of the United States, and a resident of Camden, in the county of Camden and State of New Jersey, have invented a new and Improved Tube-Making Machine, of which the following is a full, clear, and exact description.

This invention relates to certain improvements in machines for making tubes from strips of paper wound helically, and relates more particularly to that type of machine in which the paper is wound around a mandrel and firmly pressed against the previously-applied strip of paper by a presser belt, which has one run thereof wound one or more times around the mandrel and tubing. In machines of this character, it is customary to mount the presser belt upon two pulleys upon opposite sides of the mandrel, and to mount these pulleys upon a member movable so that the angle which the belt makes with the mandrel, may be varied to properly feed and press strips of paper of various widths. In some machines these members have been mounted to swing about the axis of one pulley as a center, while in others they have been mounted to swing about a center midway between the two pulleys. In most machines, two members are employed, and in some machines, the two members have been connected together, so that they will swing simultaneously.

The object of my invention is to facilitate and simplify the adjustment of the pulley and belt-carrying members, and to insure their simultaneous adjustment to the same angle. To accomplish this, I do not pivotally mount the pulley-carrying members, but mount them to slide lengthwise upon a base, which latter is mounted to swing about a fixed center, and to carry the pulley-carrying members bodily therewith. Furthermore, I provide means for automatically sliding each member in respect to said base as the latter turns about its center, so that the pulleys will remain at approximately equal distances from the mandrel.

My improved machine has means for transmitting motion to the pulleys and presser belts, irrespective of the relative positions of the latter in respect to the mandrel. The belts and belt-carrying members may be adjusted lengthwise of the mandrel, to vary the distance between them, and this

may be done without interfering with the proper transmission of power.

Reference is to be had to the accompanying drawings, forming a part of this specification, in which similar characters of reference indicate corresponding parts in all the figures, and in which—

Figure 1 is a side elevation of a machine constructed in accordance with my invention, a portion thereof being broken away, and the belt-carrying members being shown at right angles to the mandrel: Fig. 2 is a top plan view of the machine shown in Fig. 1, the belt-carrying members being at an angle to the mandrel and one of the presser belts being omitted, to avoid confusion in the disclosure of the parts; Fig. 3 is a transverse section through the machine; and Fig. 4 is a vertical longitudinal section through one of the pulley-carrying members.

In my improved machine I employ a table or bed 10, mounted in any suitable manner and serving to support the working parts of the machine. At one end there is rigidly mounted an upwardly-extending bracket or standard 11, and from the upper end of this standard, a mandrel 12 extends lengthwise of the machine above the bed or platform 10, and substantially parallel to the latter. Midway between the ends of the bed or platform, I mount a movable base 13, which in connection with the parts carried thereby, involves the main features of my invention.

This base 13 is shown in Fig. 1 as extending lengthwise of the bed 10, and substantially parallel thereto, but in actual use of the machine the bed will occupy a position in a horizontal plane at an angle to the general direction of the bed or frame, as is illustrated in Fig. 2. The base rests upon a transversely-extending supporting portion 14 on the bed, and is free to swing around a vertically-extending sleeve 15 as a center. When the base is moved to the desired position, it may be locked in any suitable manner, as, for instance, by bolts 49 carried by the bed and movable through curved slots 50 in the base concentric with the center of the sleeve 15. This sleeve serves as a bearing for a vertical shaft 16, extending up through the center of movement of the base, and at the lower end of this shaft are intermeshing bevel gears 17, by means of which the shaft receives motion from a main drive shaft 18. The latter is mounted in suitable

hangers and extends lengthwise of the machine and may be driven in any suitable manner.

Mounted upon the upper surface of the base 13 are two guide blocks 19, 19, upon the upper surface of each of which is a dove-tailed groove. The grooves extend parallel to each other, and transversely of the general length of the base, and in each groove there is mounted a slide 20 serving to carry the pulleys and presser belts and the driving mechanism therefor. As shown more particularly in Fig. 3, each slide has an upwardly-extending bracket or arm 21 on one end thereof, and either integral therewith or rigidly secured thereto. This arm serves to support one end of a shaft 22, extending lengthwise of the member 20 above the same and parallel thereto, and it also serves to support a vertical shaft upon which is mounted a pulley 23. Motion is transmitted from the shaft 22 to the pulley-bearing shaft, by suitable intermeshing bevel gears 24. Upon the opposite end of the member 20 is an upwardly-extending bracket or arm 25, very similar to the arm or bracket 21, except that this bracket is mounted to move lengthwise of the member 20, as is indicated particularly in Fig. 4. The bracket has a dove-tailed groove in its under side, as shown in Fig. 1, and into which extends a dove-tailed flange on the member 20. A screw bolt 26 extends lengthwise of the member 20 and has engagement with a depending projection 27, so that the bracket 25 may be moved lengthwise of the member and held in any desired adjusted position. The bracket 25 serves as a support for the shaft 22, and also for a vertical shaft 28, upon which is mounted a pulley 29. Suitable intermeshing bevel gears 30 serve to transmit motion from the shaft 22 to the shaft 28 and its pulley.

For transmitting motion from the shaft 16 to the shaft 22, I employ an intermediate shaft 31 extending lengthwise of the base 13 above the upper surface of the latter and at right angles to the two shafts 22, 22. This shaft 31 is supported in a suitable bracket 32 carried by or constituting a part of the sleeve 15 and intermeshing gears 33 drive the shaft 31 from the shaft 16. The shaft 31 extends beneath each shaft 22 and carries two worms 34, 34, which intermesh with worm wheels 35 on the shafts 22. The shaft 31 is supported in suitable bearings 36 on the blocks 19, and the shafts 22 may be supported intermediate their ends by suitable bearings 37, also mounted on the blocks 19. The worm wheels are keyed, so that they may slide lengthwise of their respective shafts 22, so that each sliding member with its shaft 22 and pulleys may move lengthwise in the supporting block 19, without interfering with the proper transmission of

motion to the pulleys. Also, the bevel gear 30 on the shaft 22 is keyed, so that the bracket 25 may be moved, and the worms 34 are keyed, so that they may move lengthwise of the shaft 31. To permit of this last-mentioned motion, each block 19 is provided with a dove-tailed flange on its under surface, to fit into a dove-tailed groove in the base, as is indicated particularly in Figs. 3 and 4. Two screw bolts 38, 38 extend inwardly from the ends of the base and engage in the blocks 19, so as to permit the latter to be moved toward or from each other, and thus, to vary the distance between the longitudinally movable members 20, 20. 80

From the construction so far described, it will be seen that the base 13 is free to rotate about the shaft 16 as a center, and that it carries with it the shaft 31. The base 13 in swinging, swings the two members 20, 20 85 simultaneously, and holds them in parallelism, and the swinging movement does not interfere with the free transmission of power to all of the pulleys. In order that during the swinging movement, the two pulleys of each member 20 will be kept substantially equidistant from the mandrel 12, which passes between them, the bed 10 is provided with two grooves 39 and 40 in its upper surface adjacent opposite sides and 95 adjacent opposite ends.

One of the members 20 has a depending flange 41 carrying a roller 42 movable within the groove 40, and the other member carries a similar flange 43 at its opposite end and on the lower end of this last-mentioned flange is a roller 44 in the groove 39. By the engagement of the rollers 42 and 44 in the two grooves, it will be seen that as the base 13 swings together with the members 20, the latter will be forced to move lengthwise along their respective bearing blocks 19 and in a direction opposite to the direction of swing of their respective ends of the base 13. Thus, the base swings the members 20, but the rollers and grooves prevent them from being carried to one side, and maintain the pulleys at substantially equal distances from the mandrel during any ordinary adjustment of the machine. 110

The operation of my improved machine is substantially the same as that of other machines of the same general type, and a detailed description is thought to be unnecessary. 115

In making a three-ply tube, two strips of paper A and B are fed through adjustable guides 45 and 46 of any suitable character, to the mandrel 12, and at an angle dependent upon the width of the strips. A belt 47 encircles the two pulleys 23 and 29 of the first member 20, and one run of the belt passes one or more times around the freshly wound paper on the mandrel. The belt serves to feed the paper lengthwise of the 120 125 130

mandrel, and to firmly press the second layer upon the first, so that the adhesive between the two layers will properly permeate them and hold them together. The two-ply tube is fed along the mandrel to a point adjacent the second member 20, where a third strip of paper C is fed through a suitable adjustable guide 48. A second belt, not shown in Fig. 2, but similar to the belt 47, presses this third layer in place and feeds the tube off the free end of the mandrel.

My improved machine is capable of universal adjustment and when adjusted, the parts are firmly held in position. The two belt-carrying members 20, 20 remain in parallelism at all times, and, therefore, in adjusting the machine no care need be exercised in this regard. The rollers 42 and 44 insure the proper lengthwise movement of the slides during the swinging of the base, so that this point needs no particular attention. In adjusting the machine, it is only necessary to swing the base 13 to the desired angle, and in some cases, it may be necessary to adjust the blocks 19 toward or from each other, or to tighten or loosen the belts.

Having thus described my invention, I claim as new and desire to secure by Letters Patent:

1. A machine for making coiled paper tubes, having, in combination, a mandrel, a base mounted to swing in a horizontal plane, two presser belts, and two relatively movable separate belt carriers bodily movable with said base, to vary the angle of the belts in respect to the mandrel.

2. A machine for making coiled paper tubes, having, in combination, a mandrel, two presser belts, pulleys therefor, a pivoted base, and two pulley-carrying members carried bodily by said base during the movement of the latter around its pivotal center, and movable relatively to each other along the base.

3. A machine for making coiled paper tubes, having, in combination, a mandrel, two presser belts, pulleys therefor, a pivoted base, and two pulley-carrying members carried bodily by said base during the movement of the latter around its pivotal center, and movable toward and from said pivotal center.

4. A machine for making coiled paper tubes, having, in combination, a mandrel, two presser belts, pulleys therefor, a pivoted base, and two pulley-carrying members carried bodily by said base during the movement of the latter around its pivotal center, and movable upon said base transversely of the mandrel.

5. A machine for making coiled paper tubes, having, in combination, a mandrel, two presser belts, pulleys therefor, and two relatively movable belt-carrying members

mounted to swing about a common center, to vary the angles of the belts in respect to the mandrel, and movable toward and from said center.

6. A machine for making coiled paper tubes, having, in combination, a mandrel, two presser belts, pulleys therefor, and two belt-carrying members mounted to swing about a common center, to vary the angles of the belts in respect to the mandrel, and movable to adjust the belts lengthwise, and to vary the positions of the pulleys in respect to the mandrel.

7. A machine for making coiled paper tubes, having, in combination, a mandrel, a pivoted base, a slide mounted thereon and extending transversely of the mandrel, and a presser belt carried by said slide, said slide being automatically moved across the base during the movement of the latter about its pivot.

8. A machine for making coiled paper tubes, having, in combination, a mandrel, two independent presser belts, pulleys therefor, and separate relatively movable supports for the pulleys of each presser belt, said supports being mounted to swing about a common center substantially midway between said supports.

9. A machine for making coiled paper tubes, having, two slides held in parallelism and movable longitudinally relatively to each other, presser belts carried by said slides, and a mandrel, said slides and mandrel being mounted to permit an adjusting 100 of the angle of the belts in respect to the mandrel.

10. A machine for making coiled paper tubes, having in combination, a mandrel, two presser belts, supports therefor mounted to swing about a common center and movable longitudinally relatively to each other, and power transmitting means for both of said belts and extending through said center.

11. A machine for making coiled paper tubes, having a mandrel, two presser belts, supports therefor mounted to swing about a common center between said supports, a vertical shaft at said center, and means for transmitting motion from said shaft to both of said belts.

12. A machine for making coiled paper tubes, having, in combination, a base mounted to swing about a fixed center, slides mounted to move transversely on said base, pulleys adjacent opposite ends of said slides, presser belts carried by said pulleys, a shaft extending along each of said slides, connections between each of said shafts and its corresponding pulleys, a shaft extending lengthwise of said base, connections between said last-mentioned shaft and said first-mentioned shafts, and means extending through said fixed center for transmitting motion 125 to said last-mentioned shaft.

13. A machine for making coiled paper tubes, having a pivoted base, a slide mounted thereon, a presser belt carried by said slide, a stationary guideway separate from said base, and an extension on said slide for engagement in said guideway for moving said slide lengthwise during the pivotal movement of the base.

In testimony whereof I have signed my name to this specification in the presence of 10 two subscribing witnesses.

SAMUEL M. LANGSTON.
